UNITED STATES PATENT OFFICE.

KATHARINE H. OBER, OF BALTIMORE, MARYLAND.

DESIGN FOR A BALL HOLDER OR SIMILAR ARTICLE.

Application filed November 6, 1926. Serial No. 19,632. Term of patent 7 years.

To all whom it may concern:

Be it known that I, KATHARINE H. OBER, a citizen of the United States, residing in the city of Baltimore and State of Maryland, have invented a new, original, and ornamental Design for a Ball Holder or Similar Article, of which the following is a specification, reference being had to the accompanying drawing, forming part thereof.

I claim:

The ornamental design for a ball holder or similar article, as shown.

(Miss) KATHARINE H. OBER.
